TO GEORGE MICHEL BADEAU AND ONE-THIRD TO JOSEPH AMIDIE
THERIEN, OF SOREL, CANADA.

HAT-FASTENING DEVICE.

No. 811,043.

Specification of Letters Patent.

Patented Jan. 30, 1906.

Application filed February 20, 1905. Serial No. 246,551.

To all whom it may concern:

Be it known that I, ELOUILD DUPLESSIS, of Sorel, Province of Quebec, Canada, have invented certain new and useful Improvements 5 in Hat-Fastening Devices; and I do hereby declare that the following is a full, clear, and exact description of the same.

The invention relates particularly to hat-fastening devices adapted to be carried by the hat, and may be said briefly to consist of a rigid comb-plate pivotally mounted upon a resilient wire the particular contour of which binds the comb-plate to any position to which it may be moved, while such resilient wire is fastened by a hat-pin or other means to the hat.

For full comprehension, however, of the invention reference must be had to the accompanying drawings, forming a part of this 20 specification, in which like characters indicate like parts, and wherein—

Figure 1 is an elevation of my improved fastening device and a portion of a hat, the fastening device being illustrated in an open state. Fig. 2 is a vertical sectional view taken on line B B, Fig. 1, and illustrating the fastening device in a closed state; and Fig. 3 is a top view of the hat pin or fastening device.

My improved comb-plate consists, preferably, of a curved comb *b*, with the back *c* thereof folded upon itself and extended and tapered, as at *d* to provide a thumb-piece, while the space inclosed by the folded-over back presents a straight groove. This comb-plate 35 is fastened to the hat by means of a resilient wire, the main length *f* whereof is slightly curved, and the ends thereof are bent toward one another, as at *g*, and then back toward the main length *f* again, as at *h*, and formed with 40 depressions *i* near their ends. The hat-pin I prefer to use is indicated at *n*, and the point thereof is bent, as at *o*, out of line with the body thereof.

In assembling the parts the main length of 45 the resilient wire carrier is forced into the space inclosed by the comb-plate and the carrier is then placed in position upon the side of the hat and secured in place by the pin, as shown in the drawings, the bent end of the 50 pin facilitating the fastening thereof in place.

The particular contour of the bent resilient wire causes the hat-pin to impart additional friction between the comb-plate and the car-

rier, owing to the latter being slightly bowed in the straight inclosing portion of the plate. 55

What I claim is as follows:

1. A hat-fastening device consisting of a resilient carrier adapted to be fastened to the hat and constructed to present a bowed portion, and a pivoted rigid comb-plate carried 60 by such carrier and constructed to present a straight fold or channel inclosing and fitting revolvably and snugly upon the bowed portion of the carrier for the purpose of enabling the comb-plate to be retained by the carrier 65 in different angular positions relatively to such carrier.

2. A hat-fastening device comprising a resilient carrier consisting of a length of wire bent to present a bowed portion and attachment portions, and a rigid comb-plate formed with a straight fold inclosing and fitting revolvably upon the bowed portion of the wire for the purpose of enabling the comb-plate to be retained in different angular positions relative to such carrier. 75

3. A hat-fastening device consisting of a resilient wire having its main length bowed and the ends thereof bent toward one another and then back toward the bowed portion and 80 formed with depressions near their ends, a rigid comb-plate consisting of a curved comb with the back thereof folded upon itself to present a straight groove inclosing the bowed portion of the carrier, and means whereby said 85 carrier is fastened to a hat.

4. A hat-fastening device consisting of a resilient wire having its main length bowed and the ends thereof bent toward one another and then back toward the bowed portion and 90 formed with depressions near their ends, a rigid comb-plate consisting of a curved comb with the back thereof folded upon itself to present a straight groove inclosing the bowed portion of the carrier, and extended and tapered to provide a thumb-piece, and a hat-pin 95 having its point bent for fastening the device to a hat.

In testimony whereof I have signed my name to this specification in the presence of 100 two subscribing witnesses.

ELOUILD DUPLESSIS.
